UNITED STATES PATENT OFFICE.

EDWIN E. SLICK, OF WESTMONT BOROUGH, PENNSYLVANIA.

MINE-CAR CONSTRUCTION.

1,261,308.

Specification of Letters Patent.

Patented Apr. 2, 1918.

Original application filed June 9, 1915, Serial No. 32,998, now Patent No. 1,206,042, dated November 28, 1916.
Divided and this application filed November 18, 1915. Serial No. 62,084.

To all whom it may concern:

Be it known that I, EDWIN E. SLICK, a citizen of the United States, residing in the borough of Westmont, in the county of 5 Cambria and State of Pennsylvania, (whose post-office address is Johnstown, Pennsylvania,) have invented new and useful Improvements in Mine-Car Constructions; and I do hereby declare the following to be a 10 full, clear, and exact description of the invention, such as will enable others skilled in the art to which it appertains to make and use the same.

This application is a division of my application filed June 9, 1915, Serial No. 15 32,998 for mine car.

My invention relates to mine or other cars, with particular reference to those made of metal, whereby a light, strong, 20 economical and convenient car is produced.

One of the objects of my invention is to provide a car body of simple, but at the same time, light form of construction, which shall be stiff enough to carry the 25 lading, and one which is so fashioned that a part of the car floor serves as a center sill to transmit buffing and pulling stresses and at the same time gives strength and stiffness to the car floor and the body thereof 30 to enable it to transmit the weight of the lading to the axles and wheels without undue deflection.

At the same time the center sill provides a suitable receptacle for the draft rigging, 35 inclosing and guiding the inner ends of the same, and to which the forward and rear stop plates are attached.

The features above mentioned may be 40 readily understood by reference to the annexed sheet of drawings, which forms a part of the specification and in which like characters of reference refer to like parts.

Figure 1 is a partial vertical longitudinal 45 sectional elevation showing a part of my car in which the draft rigging, stop plates, and supporting plate are shown in relation to the body of the car; Fig. 2 is a top plan view of the draft gear and the draft gear supporting plate viewed from the car bot-

tom. The draft gear is shown as equipped 50 with a set of corrugated plate friction springs, such as form the subject matter of my Patent No. 1,139,732, of May 18, 1915.

Fig. 3 is a vertical transverse sectional elevation taken on the line III—III of Fig. 1; Fig. 4 is a blank form of my bumper showing the shape and punching, before bending by solid lines, and after bending into final form by the dotted and solid line; Fig. 5 is a section taken on the line V—V 60 of Fig. 2, showing the rear view of the bumper in place.

Referring now to the characters of reference on the drawings:—1 is the car body in general, the side plates being shown integral with the bottom, while the end plates are formed of separate pieces, shaped as shown, and attached to the bottom and sides by means of rivets as illustrated. It, however, is readily understood that I may form 70 my car body from a single piece of metal if desired. The side-plates flare outwardly and the top edges thereof are crimped to stiffen the construction, prevent deformation in service, and to form a neat, smooth 75 and serviceable finish, and the end plates, likewise, have their top edge crimped for the same purposes. 2 is the center sill of inverted trough shape, preferably embossed or struck up integrally from the bottom plate, or of built up section and riveted to the floor plates. 3 is the draft gear supporting plate, which is shown as of channel form with laterally extending flanges, whereby it is connected to the car bottom by 80 means of the bolts 4.

The forward and rear stop plates 5, 6, 8 and 9 are secured to the car bottom and supporting plate by the rivets 7 and 10, 11 is a U shaped bumper plate secured to the yoke 90 16 by the rivets 12. 13 is the front follower plate, 14 is the rear follower plate, and 15 represents the corrugated friction spring plates alternately arranged with the axes of their corrugations at an angle with each 95 other. The draw bar yoke 16 has its inner end 17 reduced, and a filler plate 18 is inserted between it and the rear follower

plate; 19 indicates the outer end of the draw bar, curved to form a bearing for the buffing face piece 21 of the bumper 20.

Referring now to Fig. 4, a single piece of metal 29 is stamped or cut out to the shape indicated from which to form the draw-head and buffer. The bead or T end is bent so as to be substantially perpendicular to the plane of the buffer block 23, forming the buffing surface 21. The outer ends of the buffing plate are bent inwardly so as to provide curved end surfaces. This enables the surfaces of two adjoining buffers to bear against each other on exceedingly sharp curves, such as occur in mine track construction without danger from the plates hooking when the cars are passing from a curve to a tangent or into a reverse curve. To form the clevis 26 the opposite end of the metal piece is bent over into a goose neck curve, and provided with the perforations 27 and 28 for the coupling pin. The flanges 24 are bent downwardly to fit over the yoke members and are secured thereto by the rivets 25.

Although I have described and illustrated my invention in considerable detail, I do not wish to be limited to the exact details of construction specified, but may use such modifications in, substitutions for or equiv-

alents thereof as are embraced within the scope of my invention, or as pointed out in the claim.

Having thus described my invention, what I claim and desire to secure by Letters Patent is:—

A draft rigging comprising a rectangular bar bent into U-shape with the extremities of its free ends extending outwardly in opposite directions, an integrally formed draw-head and buffer secured to said ends, comprising an upper portion, an end portion extending downwardly therefrom and adjacent to the out-turned ends of said U-bar, a pair of downwardly projecting side portions contiguous and secured to the sides of the U-shape bar near the ends thereof, said draw-head being provided with an integrally formed clevis member, the upper portion of which is substantially parallel to the upper portion aforesaid, and coupling pin openings in said clevis member and the upper portion below same.

In witness whereof I have hereunto set my hand in the presence of two witnesses.

EDWIN E. SLICK.
